UNITED STATES PATENT OFFICE.

HOWARD A. THOMPSON, OF EDGEWOOD, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 15, 1924, Serial No. 732,196. Renewed October 21, 1926.

My invention relates to railway traffic controlling apparatus, and particularly to apparatus of the type comprising a track relay responsive to a difference of potential 5 between the track rails.

One feature of my invention is the provision of means for maintaining substantially constant the voltage applied to such relay when said potential varies.

10 I will describe one form and arrangement of apparatus embodying my invention, and will then point out the novel features thereof in claims.

15 The accompanying drawing is a view, partly diagrammatic and partly in perspective, showing one form of railway traffic controlling apparatus embodying my invention.

20 Referring to the drawing, the reference characters 1 and 1^a designate the track rails of a stretch of railway track over which the traffic moves in both directions. A track section A—B is separated from the rest of the stretch by means of insulated joints 2—2 25 interposed in the two track rails.

The section A—B is provided with trackway circuits intended for co-operation with train carried governing means responsive to the presence of alternating current in the 30 track rails. Since such governing apparatus is usually controlled by the trackway currents through the medium of suitable receiving apparatus carried on the train in advance of the forward axle, and since 35 trains proceed in both directions over section A—B, it follows that means must be provided for supplying the track section with alternating current at each end of the section. I accordingly provide the section 40 with two track transformers T' and T², located at the left hand and right hand ends, respectively, of the section and each having a secondary winding 4 constantly connected across the rails at the adjacent end of the 45 section. An impedance 3 is interposed between the secondary 4 of each track transformer and one rail 1^a of the associated section A—B in the usual manner.

The supply of alternating current to the 50 two track transformers T' and T² is controlled by an auxiliary relay S controlled by means forming no part of the present invention and omitted from the drawing for the sake of simplicity. This relay is so con-

trolled that the relay is normally de-energized 55 but is energized when a train moving from right to left enters section A—B and is retained in the energized condition as long as the train occupies the section. As shown in the drawing, relay S is de-energized and 60 under these conditions transformer T' is de-energized but transformer T² is energized, its primary winding 5 being connected, over back contact 6—8 of relay S, with terminals J and K of a suitable source of alternating 65 current not shown in the drawing. When relay S is energized, transformer T² is de-energized but transformer T' is then supplied with current from terminals J and K 70 over front contact 6—7 of relay S. It will 75 thus be plain that when section A—B is occupied by a train moving from left to right or is unoccupied, alternating current is supplied to the section from transformer T², but that when the section is occupied by a train 80 moving from right to left the alternating current is supplied to the rails by transformer T'.

Section A—B is further provided with a track relay R arranged to receive energy 80 from the track rails at a point adjacent transformer T'. Due to the impedance of the track rails, and to the leakage through the track ballast, the difference of potential 85 between the rails of the section A—B at point A will be considerably greater when the section is being supplied with alternating current from transformer T' than when transformer T² is supplying the current to the section. In the absence of any 90 preventative means this widely varying difference of potential would be applied to the terminals of the relay and might damage it. This condition is undesirable and I therefore provide a regulating transformer D to 95 maintain substantially constant the voltage applied to the relay irrespective of variations in the difference of potential between rails at point A. This transformer D comprises a continuous magnetizable core 9 having 100 a first leg 11 carrying a primary winding 15 connected across the rails adjacent point A. Opposite to leg 11 is a second leg 10 so designed and proportioned that for 105 normal values of potential difference between rails at point A, that is, when transformer T² is energized, the leg 10 is magnetically saturated. The transformer D

also comprises a magnetic leakage member 12 of magnetic material which member forms a shunt around leg 11 of core 9. The member 12 is separated from the core 9 by two air gaps 13 and 13^a and carries a secondary winding 14. A portion of the flux created by winding 15 threads winding 14 and induces therein an electromotive force. Secondary winding 14 is connected in series with relay R, and the relay and winding 14 are in turn connected across winding 15 in such manner that the voltage induced in winding 14 is opposed to the voltage applied to winding 15 from the track rails.

15 The parts are so proportioned that when section A—B is supplied with alternating current from transformer T², the voltage across relay R is of the proper value for operating relay R and the magnetic flux in core 9 is of such value that leg 10 is saturated. Then if the voltage across the rails at point A increases, as by the energization of transformer T', the increased potential difference between the rails at point A causes 20 an increase in the current through winding 15 which results in an increased flux through leg 11. Leg 10 is, however, saturated and so the larger part of the additional flux threads through member 12 thus increasing the voltage induced in winding 14. Since this voltage opposes the voltage supplied from the rails, the result is that the increase in difference of potential effective at the terminals of the relay is less than the actual increase 25 in the difference of potential between rails.

25 The ratio of turns in windings 15 and 14 is so chosen that a given increase in voltage applied to winding 15 causes an equal increase in the voltage induced in winding 14. 30 With this arrangement it is plain that the voltage applied to the terminals of relay R is substantially constant over a wide range of variation in the potential difference between rails.

35 The relay R may be used to control apparatus not shown in the drawing, such as a trackway signal, in any desired manner.

I do not, in the present application, make any claim for the broad combination of the 40 transformer D with any source of current and any electro-responsive device, such invention being claimed in my co-pending application filed on the 13th day of February, 1925, Serial No. 8918, for voltage regulating apparatus.

45 Although I have herein shown and described only one form and arrangement of railway traffic controlling apparatus embodying my invention, it is understood that various changes and modifications may be made therein within the scope of the appended claims without departing from the spirit and scope of my invention.

Having thus described my invention, what 55 I claim is:

1. In combination, a section of railway track, a track relay connected across the rails of said section, means for creating an alternating difference of potential across the rails of said section, and a transformer for 70 maintaining the voltage across said relay substantially constant when said difference of potential is varied, said transformer having a secondary winding connected in series with said relay and a primary winding connected in parallel with said relay.

2. In combination, a section of railway track, a track relay connected across the rails of said section, means for creating an alternating difference of potential across the 80 rails of said section, and a transformer for maintaining the voltage across said relay substantially constant when said difference of potential is varied, said transformer having a secondary winding connected in series 85 with said relay and a primary winding connected in parallel with said relay and said secondary winding.

3. In combination, a section of railway track, a track relay connected across the 90 rails of said section at a point, means for creating an alternating difference of potential between the rails of said section the magnitude of which difference of potential is variable at said point, a continuous magnetizable core having a first leg carrying a primary winding connected in parallel with 95 said relay, and having a second leg that is magnetically saturated when the difference of potential across said relay is of a normal value, a magnetizable leakage member shunting said first leg, and a secondary winding on said member and connected in series with said relay in such manner that the voltage induced in said secondary is opposed to the potential applied to the relay from the rails.

4. In combination, a section of railway track, means for supplying alternating current to the rails of the section so that the difference of potential between the rails at a given point is variable, a track relay connected across the rails at said point, a transformer comprising a core having a first leg carrying a primary winding connected in parallel with said relay and having a second leg that is magnetically saturated at normal values of the difference of potential between the rails at said point, a magnetic leakage member shunting said first leg, and a secondary winding on said member connected in series with said relay.

5. In combination, a section of railway track provided with two track transformers one connected across the rails adjacent each end of the section, means for selectively energizing one or the other of said transformers to create an alternating difference of potential between the rails, a transformer comprising a core having a first leg 125

carrying a primary winding which is connected across the rails adjacent one end of the section, and a second leg that is magnetically saturated when the transformer at the other end of the section is energized, a magnetic leakage member shunting said first leg, a secondary winding on said leakage member, a track relay connected in series with said secondary winding, said relay and said secondary being connected in parallel with said primary winding.

In testimony whereof I affix my signature.

HOWARD A. THOMPSON.
